(57) **CLAIM**

The ornamental design for the carry bag, as shown and described.

DESCRIPTION

FIG. 1 is an isometric view of my carry bag in an unexpanded form showing my new design;

FIG. 2 is a top plan view of the design of FIG. 1;

FIG. 3 is a left side elevational view of the design of FIG. 1;

FIG. 4 is a right side elevational view of the design of FIG. 1;

FIG. 5 is a bottom plan view of the design of FIG. 1;

FIG. 6 is a front side view of the design of FIG. 1; and

FIG. 7 is a back side view of the design of FIG. 1.

FIG. 8 is an isometric view of the design of FIG. 1 in an expanded form;

FIG. 9 is a top plan view of the design of FIG. 8;

FIG. 10 is a left side elevational view of the design of FIG. 8;

FIG. 11 is a right side elevational view of the design of FIG. 8;

FIG. 12 is a bottom plan view of the design of FIG. 8;

FIG. 13 is a front side view of the design of FIG. 8; and,

FIG. 14 is a back side view of the design of FIG. 8.

A zipper, pouch and handle are shown in dashed lines for illustrative purposes only, and are not part of the claimed design.
